UNITED STATES PATENT OFFICE

156,435

ADJUSTABLE CHAIR FOR CEREBRAL
PALSID CHILDREN

Louis H. Klein, Millbrae, Calif.

Application September 20, 1948, Serial No. 148,658

Term of patent 3½ years

(Cl. D15—3)

To all whom it may concern:

Be it known that I, Louis H. Klein, a citizen of the United States of America, residing at Millbrae, in the county of San Mateo and State of California, have invented a new, original, and ornamental Design for an Adjustable Chair for Cerebral Palsied Children, of which the following is a specification, reference being had to the accompanying drawing, forming a part thereof.

The figure is a perspective view of a chair of the character described showing my new design.

I claim:

The ornamental design for an adjustable chair for cerebral palsied children, substantially as shown.

LOUIS H. KLEIN.
